CORRUGATED WALL STRUCTURE

Filed Oct. 13, 1930

UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

CORRUGATED WALL STRUCTURE

Application filed October 13, 1930. Serial No. 488,291.

My invention relates to the construction of railway cars, and more particularly to metal end structures or walls for railway cars made of one or more metallic plates or panels formed with integral reinforcing, stiffening and bracing embossments or corrugations. However, this device may be incorporated in the construction of car side walls, floors, roofs, or doors used in connection with rail-
way cars of various types.

An object of the invention is to produce a strong metallic wall which is too large to economically be made of a single plate and to strengthen such wall by forming therein a plurality of contiguous substantially parallel corrugations or embossments, and furthermore, to produce a wall having equal strength per linear measurement transverse to the corrugations; that is, after the plates are united, a cross section through them presents a plurality of contiguous corrugations of equal width and of equal depth. This I accomplish by forming each plate (two or more) with a plurality of contiguous equal width and equal depth corrugations and arranging a corrugation in each plate so that the margin of such corrugation is at the edge of the plate and butt welding the plates together. If the margins of the plates have been drawn in or deformed by the corrugating process they are sheared to a straight edge at the desired place before welding.

Another object is to save the expense of the usual riveted lap joint which involves the extra material for lapping the plates, the punching of the rivet holes, the material of the rivets, as well as the labor of riveting.

It is common knowledge and practice to produce a very strong and relatively light wall by forming a plurality of parallel sinuous corrugations in a relatively thin metallic plate, but there is an economic limit in the width and length of such steel plates beyond which they cannot be obtained at prices which justify their use for such purposes. For instance, such corrugated plates are quite generally used as end walls for railway box cars, which walls are approximately nine feet square and six feet is about the widest plate that can be obtained without paying prohibi-

tive extra prices to the comparative few mill owners who can roll such plates, which also means delay in delivery. It is customary, therefore, to form such end walls for railway box cars by separately corrugating two or more metallic plates and lapping the adjacent margins of the plates about three inches and securing them together by five-eighth inch rivets spaced three inches apart. Such fastening means is expensive in both labor, material and time. Another serious objection to this method of producing such an end wall is that the two corrugations on opposite sides of the lap joint are necessarily spaced further apart than the corrugations in the remainder of the plates, which results in a relative "weak spot" in the end wall because the strength of the corrugated plate per linear measurement transverse of the car is less at the lap joint than elsewhere. In actual figures, as commercially used today, most of the corrugations in the end wall are spaced on six inch centers, whereas, the corrugations on opposite sides of the seam are spaced on nine inch centers. This three inch lap cannot be reduced because the distance of the rivet from the edge of the plate, the thickness of the plate and the size of the rivet are all in accordance with known and established engineering standards.

In the drawings:

Fig. 1 shows two corrugated plates already sheared and ready for welding.

Fig. 2 is a section on line 2—2 of Fig. 1.

Fig. 3 is a similar section showing the same two plates welded together.

Fig. 4 is a similar section through similar plates wherein the plates are formed with alternate corrugations projecting in opposite directions from the original plane of the plate.

Fig. 5 shows the two plates of Fig. 4 welded together.

Fig. 6 shows two corrugated plates formed with my improved divided corrugations as disclosed and claimed in my Patent No. 1,681,811 of August 21, 1928, which plates are sheared and ready for welding.

Fig. 7 is a section on line 7—7 of Fig. 6.

Fig. 8 is a section on line 8—8 of Fig. 6.

Figs. 9 and 10 are sections similar to 7 and 8 respectively showing the same two plates welded together.

Figs. 1 and 2 show a pair of metallic plates 5 and 2, each formed with a plurality of parallel contiguous corrugations 4 of equal width 5 and equal depth 6 and spaced apart distances 7 substantially equal to their respective widths 5. Each of these plates is sheared 10 on one edge 10 on preferably a straight line parallel to the edge corrugation 11 of each plate at a distance 12 from such corrugations substantially half of the distance 5 between the other corrugations.

15 Fig. 3 shows how these plates are butt welded at 15 so that the distance 16 between the corrugations 11—11 adjacent such butt weld is substantially equal to the distance 7 between the other corrugations and the 20 united plates thereby forming a wall of equal strength per linear measurement transverse to the corrugations. When a load is imposed upon one of the corrugations in such a corrugated plate in a direction transverse to the plane of the plate, such load is partially transferred to the adjacent corrugations, therefore, it is essential that the corrugations be contiguous. It is also essential that the wall be of equal strength per linear 30 measurement transverse to the corrugations because if there is any weak place in the wall it would deflect at such place.

Fig. 4 shows a pair of plates wherein the corrugations 20 are pressed partially inwardly and partially outwardly from the original plane 21 of the plate, and Fig. 5 shows how these two plates are butt welded together at 22 to form a wall having a plurality of contiguous corrugations.

40 Fig. 6 shows a modified form wherein a pair of plates 30—31 is provided with a plurality of divided corrugations, as disclosed and claimed in my Patent No. 1,729,313 of September 24, 1929. These plates are 45 formed with a plurality of parallel contiguous corrugations 33 spaced apart distances 34 substantially equal to their width 35 adjacent the middle of the plate, as shown in Fig. 7. These corrugations are divided adjacent their opposite ends into a plurality of a greater number of shallower contiguous corrugations 37, as shown in Fig. 8. The respective plates are sheared at one edge 38 of each plate preferably on a straight line 55 substantially parallel to the axes of these divided corrugations and at a distance from said corrugations substantially half 40 of the distance 34 between the other corrugations.

60 Figs. 9 and 10 show these plates after they have been butt welded together at 43 to form a wall having a plurality of contiguous corrugations.

65 The accompanying drawings illustrate the preferred form of the invention, though it

is to be understood that the invention is not limited to the exact details of construction shown and described, as it is obvious that various modifications thereof within the scope of the claims will occur to persons skilled in the art.

I claim:

1. The method of providing a wall by forming each of two plates with a plurality of substantially parallel corrugations spaced 75 equi-distant apart and then welding said plates together substantially midway between two of the corrugations.

2. The method of forming a wall of two corrugated plates wherein each plate is provided with a plurality of substantially parallel corrugations spaced equi-distant apart, by first corrugating the plates separately; secondly, shearing one edge of each plate parallel to the edge corrugation of each 85 plate and at a distance from said corrugation substantially half of the distance between the other corrugations, and thirdly, butt welding the sheared edges of the plate together.

3. A wall comprising two plates welded 90 together, each formed with substantially parallel corrugations, the distance between the two corrugations adjacent the weld being substantially the same as the distance between the other corrugations in the two 95 plates.

4. In a corrugated metallic plate wall, the method of producing a wall of uniform strength per linear measurement transverse to the corrugations when the wall comprises 100 two plates by forming each plate with contiguous equal width and equal depth corrugations with the margin of one corrugation in each plate at the edge of such plate and butt welding said plates together whereby a cross section of the united plates presents a plurality of contiguous corrugations of equal width and of equal depth.
